VICTOR E. HANSEN, OF HOQUIAM, WASHINGTON, AND ONE-EIGHTH TO HARRY H.
WILT, OF COSMOPOLIS, WASHINGTON.

PUMP.

Application filed February 23, 1927. Serial No. 170,351.

This invention relates to improvements in pumps, and more particularly to what are commonly known as rotary pumps; it being the principal object of this invention to provide a pump of that character wherein a revolvably mounted rotor operates to draw into and forcibly deliver water from the pump casing, and wherein the rotor mechanism operates in perfect balance due to the fact that it is located centrally within its casing as distinguished from being eccentrically mounted as is the case with practically all rotary pumps now in use.

More specifically stated, the object of the invention resides in the provision of a rotary pump comprising a cylindrical casing having inlets and outlets at diametrically opposite points and wherein a rotor disc is revolvably fitted which carries a plurality of spaced apart, radially disposed impeller plates adapted to move transversely with respect to the disc and which extend at opposite sides of the latter into contact with cover plates fitted to and closing the ends of the casing; the cover plates being provided on their inner sides with correspondingly formed, annular cam surfaces which are spaced substantially from the surface of the disc adjacent the inlet openings, but which gradually draw into close relation thereto adjacent the outlets, so that annular, wedge-like passages are provided at opposite sides of the rotor disc into which water may be drawn incidental to operation of the rotor and from which it is then forcibly discharged through the outlets by the driving action of the impeller plates.

Other objects of the invention reside in the various details of construction and combination of parts and in their mode of operation, as will hereinafter be described.

In accomplishing these and other objects of the invention, I have provided the improved details of construction, the preferred forms of which are illustrated in the accompanying drawings, wherein—

Figure 1 is a central, vertical section of a pump embodied by this invention; the section being taken in the longitudinal direction of the rotor shaft.

Figure 2 is an end view of the pump.

Figure 3 is a transverse, sectional view taken substantially on the line 3—3 in Figure 1.

Figure 4 is a longitudinal section, showing

parts of the pump in disconnected relation for the purpose of better illustrating the rotor and the cam surfaces provided on the opposite cover plates.

Figure 5 is a flattened-out, sectional view taken on the radially curved line 5—5 of Figure 3, graphically illustrating the wedge-like passages between the rotor disc and the cover plates of the casing and the function of the impellers for drawing the water into and driving it from these passages as the rotor revolves.

Referring more in detail to the drawings—

1 designates a cylindrical casing having an integrally formed base flange 1^a whereby it may be secured upon a foundation or support. Within the casing, a rotor disc 2 is centrally located and revolvably fitted, and which has a peripheral rim portion 3 that is revolvable between two ring-like guide pieces 4—4' that are secured within the opposite ends of the cylindrical casing. The rotor disc is equipped with a central hub portion 5 by which it is fixed on a rotor shaft 6 that is revolvably supported in bearings 7—7' which may be of any suitable, anti-friction type and which, preferably, are supported by brackets 8—8' formed integral with or extending from cover plates 9—9' that are fitted over the opposite ends of the casing 1. These cover plates 9—9' are drawn tightly against the casing and are held in place by a plurality of bolts 10 which may extend through the casing from one plate to the other, as shown in Figure 1, or may be threaded into the casing as is desired. Suitable gaskets 11 are located between the edges of cover plates and the ends of the casing to prevent leakage through the joints. The plates are also provided with outwardly extended hub portions 12 provided with aligned bores 13 through which the rotor shaft 6 extends, and these are equipped with packing glands, as at 14, to prevent leakage about the shaft. The glands are tightened in place by cup nuts 15 threaded on the ends of the hubs and these may be locked in place by locking rings 16 that are also threaded onto the hubs.

Formed on the inner side of the cover plates 9—9', respectively, are hub portions 18—18' that extend into close contact with the opposite sides of the rotor disc, and suitable packing plates, as designated at 19, are located between the ends of these hubs and the adja-

cent sides of the disc as a means of preventing leakage and also preventing wear on the parts. Also, the ends of these hubs are counterbored, as at 20, to provide recesses 5 into which the ends of the rotor hub 5 extends, as shown in Figure 1, and additional packing plates of a suitable character, as designated at 21, are located between the ends of the hub 5 and the bases of these recesses 10 to give additional security against wear and leakage.

The rotor disc 2 is located centrally between the opposite cover plates 9-9' and opening into the casing wall at diametrically 15 opposite sides with respect to the rotor shaft, are elongated slots 25 and 26 which are the outlet passages for the delivery of water from the casing. These lead, respectively, into channels 27 and 28 which are formed in 20 the casing and which lead into a chamber 29 in the base of the casing with which an outlet, or discharge, pipe 30 connects. The outlets 25 and 26 are located on opposite sides of the disc, in order to take care of the water dis- 25 charged from the annular passages at opposite sides of the disc.

Inlets 35 and 36 are provided, respectively, in the hub portions 18-18' of the cover plates 9-9' and these open into the annular chambers at opposite sides of the disc at points opposite the respective inlets into the chambers. The inlets 35 and 36 open from channels 35' and 36' which lead downwardly into 30 chambers 37-37' formed in the cover plates 35 9-9' and pipes 38 are threaded into these chambers for the delivery thereto of water from a source of supply. The channels 35' and 37' are joined through the casing by 35 means of a connecting channel 39 to provide 40 for an equalizing of water supply delivered to opposite sides of the rotor disc. The inlet and outlet openings extend circumferentially of the hubs and casing through approximately 45 ninety degrees as is shown in Figure 3.

Formed on the inner surfaces of the cover plates 9-9' about the hub portions 18-18', are annular cam surfaces 40-40'. These are correspondingly formed so that the distance 50 between them, measured parallel with the shaft 6, is the same at all points. Their distance from the side of the rotor disc, however, varies as is presently described.

Mounted in the rotor disc, just within the rim portion 3, is a plurality of radially disposed and equally spaced apart impeller plates 45, the opposite ends of which fit in close contact with the cam surfaces 40-40', while their inner and outer edges, respectively, closely contact with the casing wall 55 and with the outer surfaces of the hubs 18-18' so that pockets are provided at opposite sides of the disc between adjacent plates.

These cam surfaces 40-40', which are the 60 outer side surfaces of the annular channels

located at opposite sides of the rotor disc, are disposed closely to the disc throughout a part of their circumference and then gradually recede therefrom throughout the angular length of the inlets; then they continue parallel with the disc for a short distance and then gradually draw closely to the disc through the angular length of the outlets. This will be better understood by reference to Figure 5 which shows the cam surface 40 to gradually recede from the disc throughout the distance A which corresponds to the angular distance A' in Figure 3; then it continues parallel with the disc through a distance B corresponding to the angular distance B' 80 in Figure 3; then it gradually draws back close to the disc through the distance C which corresponds to the angular distance C' in Figure 3, and then it continues parallel with the disc back to the starting point. The distances A' and C', respectively, include the angular lengths of the inlet and outlet passages into the channel.

Assuming the pump to be so constructed, its operation would be as follows: With the 90 shaft 6 connected with some suitable power mechanism, it is driven revolvably in the direction indicated by the arrow in Figure 2. As the rotor revolves within the casing the impeller plates move back and forth through 95 rotor disk 2 in accordance with their travel along the cam surfaces 40-40' and as they pass over the inlet ports 35-36, the gradually increasing volume of the pockets formed between the plates creates a suction which 100 draws in water through the pipes 38, channels 37-37' and passages 35-36 into the channels at opposite sides of the disc. This water is carried with the rotor between the 105 impeller plates and is then forced from the pockets through the outlets 25 and 26 due to the decrease in their size as the cam surfaces draw inwardly toward the disc. It is readily apparent that a continued rotary motion of 110 the rotor causes a continual intaking of water through the inlets and a continual discharge through the outlets, and that the rate of flow will be dependent upon the rate of rotation.

Pumps of this character may be made in various sizes and may be equipped with any 115 required or desired number of impeller plates. Also, one, two or more inlets and outlets could be provided and cam surfaces for effecting the intake and discharge of water made in accordance with the number of such 120 inlets and outlets used.

Pumps of this character can be operated at satisfactory speed without vibration due to the balanced action of parts provided by this design. Since the places of intaking and for 125 discharging of water are located at equally spaced apart distances, any lateral force required for the pumping action at one side of the disk is counterbalanced by that at the other side. Also, it is apparent that there is 130

- no dragging or retarding pressure of the impellers against the cam surfaces as they pass the discharge ports for the reason that it is relieved due to suction at the other side of the 5 rotor which draws them in that direction. No lateral pressure is directed against the rotor by water when carried by the impellers as they travel along the cam surfaces that are parallel with the rotor.
- 10 While I have described the pump as being for water, it is readily apparent that it is just as useful for pumping any other liquid or fluid and it is not intended that it be confined only to the pumping of water.
- 15 It is further apparent that the present device is adapted for use as a rotary engine by connecting the inlet connections with a source of steam supply which will act against the impellers to drive the rotor; the steam being 20 expelled through the outlets.
- Having thus described my invention, what I claim as new therein and desire to secure by Letters-Patent, is:
1. A pump of the character described comprising a cylindrical casing, a rotor disc revolubly fitted therein, cover plates fitted over the ends of the casing and having hub portions extended inwardly into close contact with the rotor and providing annular chambers at opposite sides of the rotor disc, said 25 casing having a circumferentially extending outlet from each chamber, said outlets being located at diametrically opposite points, each of said cover plates being provided with an inlet that opens into the chamber at that side 30 circumferentially of the hub portion of the plate, said inlets being located diametrically opposite the outlets of their respective chambers, said cover plates having cam surfaces formed to extend within the annular chambers and which, through extent of the inlet ports, gradually recede from the opposite faces of the rotor and which, through the angular extent of the outlet ports, gradually draw toward the faces of the rotor, and impeller plates slidably mounted in the rotor with their ends extended into annular chambers at opposite sides thereof to serve as pump pistons for the drawing in and expelling of 35 water therefrom.
2. A pump as recited in claim 1, wherein the cylindrical casing is provided with a chamber adapted for connection with a discharge pipe from which channels lead to the outlets from the annular chambers, and 40 wherein the inlets provided in the cover plates communicate with chambers adapted to be connected with pipes from a source of supply of water, and wherein the latter 45 chambers have a connecting channel.
